(57) **CLAIM**

The ornamental design for a combined cat litter scoop holder and scoop, as shown and described.

DESCRIPTION

FIG. 1 is a front perspective view of a combined cat litter scoop holder and scoop;

FIG. 2 is a front view thereof;

FIG. 3 is a back view thereof;

FIG. 4 is a rear perspective view thereof;

FIG. 5 is a left side view thereof;

FIG. 6 is a right side view thereof;

FIG. 7 is a top view thereof; and,

FIG. 8 is a bottom view thereof.

The scoop handle is a fanciful cat's tail, and the scoop holder front is a fanciful image of a cat standing, holding up one paw.
